UNITED STATES PATENT OFFICE.

SYLVESTER ONSLOW GOULD, OF MARION, INDIANA.

MOTOR.

1,228,316.

Specification of Letters Patent. Patented May 29, 1917.

Application filed August 1, 1916. Serial No. 112,626.

To all whom it may concern:

Be it known that I, SYLVESTER ONSLOW GOULD, a citizen of the United States, residing at Marion, in the county of Grant and 5 State of Indiana, have invented a new and useful Motor, of which the following is a specification.

The device forming the subject matter of this application is an internal combustion 10 engine, and one object of the present invention is to provide novel means for controlling the passage of the explosive mixture into the cylinder, and for controlling the exit of the exhaust from the cylinder.

Another object of the invention is to provide a novel form of valve ring, combined with novel means for actuating the ring, the ring controlling the ports whereby the explosive mixture is admitted, and controlling the ports whereby the exhaust is 20 discharged.

Another object of the invention is to improve the manifolds which coöperate with the valve ring.

It is within the province of the disclosure to improve generally and to enhance the utility of devices of that type to which the present invention appertains.

With the above and other objects in view 30 which will appear as the description proceeds, the invention resides in the combination and arrangement of parts and in the details of construction hereinafter described and claimed, it being understood that 35 changes in the precise embodiment of the invention herein disclosed can be made within the scope of what is claimed, without departing from the spirit of the invention.

In the accompanying drawings:—

Figure 1 shows in elevation, an internal combustion engine whereunto the device forming the subject matter of this application has been applied, parts being broken away, and parts appearing in section;

Fig. 2 is a fragmental cross section, diagrammatic in nature, and illustrating the relative positions of the valve ring and a relatively fixed port-ring on the cylinder, when an explosion is taking place;

Fig. 3 is a bottom plan of the valve ring and attendant parts, portions appearing in section;

Fig. 4 is a view similar to Fig. 2, but illustrating the relative positions of the port-ring and the valve ring, when the explosive mixture is being admitted to the cylinder;

Fig. 5 is a sectional view resembling Fig. 4, but showing the relative positions of the port ring and the valve ring while the exhaust is taking place; and 60

Fig. 6 is a plan view showing a different portion of the actuating worm from that disclosed in Fig. 3.

In carrying out the present invention, there is provided an engine including one or 65 more cylinders 1, the numeral 2 denoting a piston operatively connected with a crank shaft 3 by means of a pitman 4, all as usual and well understood.

Any suitable means may be provided for 70 actuating the valve ring hereinafter described. In one useful but not mandatory form of the invention, the engine carries bearings 5 in which is journaled an auxiliary shaft 6 connected with the crank shaft 75 3 by means of intermeshing beveled pinions 7. Supported for rotation in bearings 26 on the engine cylinder 1 or elsewhere is a supplemental shaft 25 which, if the axis of the cylinder 1 is vertical, is horizontally 80 disposed. The supplemental shaft 25 is connected with the auxiliary shaft 6 by means of intermeshing beveled pinions 27. Mounted on the supplemental shaft 25 and secured thereto is a worm 30 including a 85 spiral thread 28 and a communicating thread 29, the thread 29 lying in a plane which is at right angles to the axis of the supplemental shaft 25. As hereinbefore intimated, the structure above described will be found useful 90 in rotating the valve ring, but the particular mechanism mentioned for rotating the valve ring may be changed, should occasion demand.

The numeral 8 denotes a relatively fixed 95 ring provided with ports 24, the element 8 being designated as a port-ring. The port-ring 8 preferably is expansible, and is divided transversely as shown at 10. The port-ring 8 is provided with a depending 100 flange 9 which engages inside of the cylinder 1. The construction, obviously, is such that, when the port-ring 8 is supported on the cylinder 1 as shown in Fig. 1, a leakage between the port-ring and the cylinder will 105 not be likely to occur.

Superposed upon the port-ring 8 is a head 11. Securing elements 12 may connect the head and the port-ring 8 with the upper end of the cylinder 1. 110

The numeral 14 has been used to designate an annular exhaust manifold which, in

cross section, is of U-shape, as Fig. 1 will clearly disclose, the manifold 14, therefore, being open at its bottom. The exhaust manifold 14 is secured in any desired manner, as shown at 15, to the head 11 of the cylinder. The exhaust pipe which communicates with the manifold 14 is indicated at 16. Disposed below the exhaust manifold 14 is an annular intake manifold 17 of U shape in cross section, the intake manifold, therefore, being open at its top. The numeral 18 denotes a conduit whereby an explosive mixture is supplied to the intake manifold 17. The manifolds 14 and 17 may be equipped peripherally with approaching flanges 19.

At 20 there appears a valve ring surrounding the port ring 8 closely but rotatably between the manifolds 17 and 14, the periphery 20 of the valve ring 20 being overlapped by the flanges 19 on the manifolds as shown in Fig. 1. The valve ring 20 is supplied with intake ports 22 of angular form, as Fig. 4 will clearly disclose. The depending portions 25 of the ports 22 communicate with the intake manifold 17, the horizontal or lateral portions of the ports 22 being alined with the ports 24 of the ring 8 and being adapted, at times, to communicate therewith. The valve ring 20 is provided with angular exhaust ports 23, the upwardly extended portions of 30 which communicate with the exhaust manifold 14, the horizontal or lateral portions of which are alined with the ports 24 of the ring 8, and are adapted at times to communicate therewith. If an operating mechanism such as the shaft 25 and the worm 30 is employed, then the valve ring 20 is equipped with peripheral teeth 21 coöperating with 35 the worm.

When the valve ring 20 is rotated into a position such that an explosive mixture may be sucked into the cylinder 1, then, as shown in Fig. 4, the inlet ports 22 of the valve ring 45 communicate with the ports 24 of the ring 8. At this time, the exhaust ports 23 in the valve ring are out of communication with the ports 24 in the ring 8. When an exhaust is taking place, the exhaust ports 23 in the 50 valve ring 20 communicate with the ports 24 of the ring 8, as shown in Fig. 5, but at this time, the intake ports 22 of the valve ring do not communicate with the ports 24. During the explosive and compression strokes 55 of the piston 2, the ports 24 in the ring 8 lie between the ports 22 and 23 in the valve ring 20 and consequently there is no communication between the interior of the cylinder 1 and the exhaust manifold 14, upon 60 the one hand, nor is there communication between the interior of the cylinder and the intake manifold 17, upon the other hand.

From the foregoing, it will be obvious that the explosive mixture passes by way of the conduit 18, the ports 22 and the ports 24 65 into the cylinder 1, and when the valve ring 20 is rotated a predetermined amount, the exhaust leaves the cylinder 1 by way of the ports 24, the ports 23, the exhaust manifold 14 and the pipe 16.

Noting Figs. 3 and 6 of the drawings, it will be understood that when a tooth 21 of the valve ring 20 traverses the spiral thread 28 of the worm 30, the valve ring 20 rotates, but during the time that the said tooth is 70 traversing the part 29 of the worm, the valve ring 20 will remain at rest. The valve ring 20 remains at rest, as above indicated, for a short interval, when the ports 22 and 24 communicate, as shown in Fig. 4, and when 80 the ports 23 and 24 communicate as shown in Fig. 5.

For convenience in claiming the invention, the port ring 8 may be considered as a part 85 of the cylinder 1, since it is fixed with respect thereto.

Having thus described the invention, what is claimed is:—

1. In an internal combustion engine, a cylinder; a ring supported on the cylinder 90 and provided with a flange engaged within the cylinder, the ring having ports; a head carried by the ring; a manifold supported by the head; a manifold assembled with the cylinder; a valve ring journaled between the manifolds, the valve ring being provided with ports which communicate respectively with the manifolds, and are adapted to communicate with the ports in the first specified 95 ring when the valve ring is rotated; and means for rotating the valve ring.

2. In an internal combustion engine, a cylinder having lateral ports; manifolds carried by the cylinder; a valve ring journaled 105 between the manifolds and provided with ports coöperating respectively with the manifolds and adapted to coöperate with the ports in the cylinder when the valve ring is rotated, the valve ring being provided with 110 peripheral teeth; a worm including a spiral thread, and a communicating thread disposed at right angles to the axis of the worm, the teeth of the valve ring coacting with the threads; means for supporting the worm 115 for rotation; and means for rotating the worm.

In testimony that I claim the foregoing as my own, I have hereto affixed my signature in the presence of two witnesses.

SYLVESTER ONSLOW GOULD.
